UNITED STATES PATENT OFFICE.

ARTHUR T. CROCKER, OF SCHENECTADY, NEW YORK, ASSIGNOR TO GENERAL ELECTRIC COMPANY, A CORPORATION OF NEW YORK.

CONTROLLER.

No. 872,329.

Specification of Letters Patent.

Patented Dec. 3, 1907.

Application filed March 3, 1906, Serial No. 304,008.

To all whom it may concern:

Be it known that I, ARTHUR T. CROCKER, a citizen of the United States, residing at Schenectady, county of Schenectady, State of New York, have invented certain new and useful Improvements in Controllers, of which the following is a specification.

The present invention relates to electric controllers and particularly to that type of controller wherein a motor circuit is arranged to be interrupted and brakes applied when the controller handle is released. In my prior application, Serial No. 240,143, filed Jan. 9, 1905, I have illustrated a controller of this general character adapted for use in so-called semi-automatic controller systems for railway service. This is a fairly large controller and certainty of operation in case of emergencies makes it expedient to provide means for operating a circuit-breaking and brake-applying apparatus independently of movements of the main controller cylinder. Where the control system is entirely automatic only a few train wires are needed and therefore the controller may be made comparatively small and the entire cylinder may be caused to return to "off" position upon release of the controller handle. The present invention comprises a novel construction and arrangement of parts forming the emergency apparatus in this latter type of controller.

It is customary for the motorman, in leaving his car, to remove either the controller handle or the handle of the reversing switch so as to prevent tampering with the controller by unauthorized persons. The handle of the reversing switch is usually small, but where the reversal of the motor is secured by reversing the main controller itself, the only handle that can be removed is the handle of the controller which is quite bulky and inconvenient for the motorman to carry about.

One of the objects of the present invention is to provide means for effectually locking a reversing controller in such a way that it is unnecessary for the motorman to remove the handle or any other bulky part.

The present invention in its various aspects will be more fully understood and its objects and advantages will more clearly appear from the following description thereof taken in connection with the accompanying drawings, wherein:

Figure 1 is a side elevation of a controller constructed and arranged in accordance with the present invention, the casing being removed to show the interior mechanism; Fig. 2 is an enlarged view showing in cross-section the controller handle and emergency and locking devices; Fig. 3 is a section taken on line A A of Fig. 1; Fig. 4 is a detail of a catch for holding the controller in its "off" position; and Fig. 5 shows the locking key carried by the motorman.

Reference being had to the drawing, 1 indicates a controller cylinder mounted upon a shaft 2 which is suitably journaled in the casing 3 of the controller. Surrounding the lower end of the shaft is a spring 4 having its opposite ends secured respectively to a fixed portion of the controller casing and to the controller cylinder, the arrangement being such that when the cylinder is turned in either direction from its central position, spring 4 is placed under tension and returns the cylinder to its normal position when free to do so. The upper end of the shaft 2 projects through the cap-plate 5 of the controller and has fixed thereto above the cap-plate the hollow handle 6.

7 indicates a valve arranged in a casing 8 and normally held closed by means of the spring 9. A valve stem 10 projects beyond the casing 8. The valve mechanism is suitably supported in the upper end of the controller casing and adjacent the controller shaft. An arm 11, pivotally mounted upon a shaft 12 journaled in lugs extending from the valve casing, is adapted to strike the end of the stem 10 and unseat the valve; this movement of the arm being effected by a spring 13 secured at one end to a fixed projection 14 and at its other end to a member 15 secured to the arm 11. Normally, this arm is held out of engagement with the valve stem by means of a pivoted catch 16 which has a shoulder 17 adapted to drop in front of the arm, holding it against the tension of the spring 13. On the controller shaft is a sliding member 18 having on its upper face a cam 19 so located that, when the member 18 is in its upper position and the controller in its "off" position, the cam is directly beneath the free end of the dog 16 and holds it out of locking engagement with the arm 11. The sliding member 18 is controlled by means of a rod 20 slidably arranged within the axial opening 21 in the upper end of the shaft of 110

the controller; the rod being secured at its lower end to the member 18 by means of a pin 22 and projecting at its other end into a jaw-shaped portion 23 at the extreme upper end of the shaft. Within the controller handle is pivotally supported a lever 24 extending into a jaw 23 and having its free end located beneath a stem 25 secured to button 26 projecting above the grip of the handle in the usual way. It will be seen that when the button in the controller handle is depressed, as shown in Fig. 2, the lever 24, pressing upon the upper end of the rod 20, holds it in its lowermost position and, therefore, maintains the member 18 and its cam 19 depressed against the tension of a spring 27 upon which the lower end of the rod 20 rests. While in this position, the controller handle may be rotated at will without causing the cam to release the catch.

In case the motorman takes his hand from the button either while the controller is in a running position or in its "off" position, the member 18 is forced upwardly by means of the spring 27 and trips the catch, for if the controller is not already in its "off" position it is turned to that position by the spring 4, causing the cam 19 to ride under the end of the catch. The tripping of the catch releases the arm 11 and permits it to unseat the valve. The unseating of the valve operates to exhaust air from the pipe 43 and causes the brakes to be applied. In order to release the brakes, the button 26 must be again depressed and the member 18, in moving downwards, engages with arms or jaws 28 which may be cast integral with or otherwise be secured to the arm 11 and member 15. Obviously, as the jaws are depressed, the arm 11 will be moved away from the valve stem against the tension of the spring 13 until the catch is free to drop into locking engagement with the arm.

The emergency valve-operating mechanism may be locked against operation by a sliding bolt 29 arranged in the controller handle and adapted to be moved through an opening 30 in the upper end of the controller shaft and to engage a recess 31 in the rod 20. This recess is so located that it registers with the opening 30 when the rod is depressed, namely when the parts are in the brake-releasing position. The bolt 29 may be arranged in various ways, as, for example, it may form part of or be secured to a plate 32 slidably mounted in the controller handle and having a shoulder 33 which is engaged by one end of a spring 34; the opposite end of the spring bearing against a fixed portion 35 of the handle. A cam-shaped opening 36 in the plate is adapted to be engaged by a key 37; the key being designed to withdraw the bolt from engagement with the recess 31 by pressing the plate outwardly against the spring 34; and the spring

in turn shooting the bolt into locking position when the key is removed.

Although the spring 4 is adapted to bring the controller to the "off" position it is advantageous to have a positive lock for holding the controller in that position after the spring has performed its function. For this purpose a pair of catches 38 and 39 are pivoted to the underside of the cap-plate and a lug 40, adapted to engage these catches 75 when the controller is in the "off" position, projects from the member 18. The lug and catches are so proportioned that when the member 18 is depressed during the normal operation of the controller, the lug is brought 80 below the plane of the catches and leaves the controller free to be rotated. When, however, the button in the handle is released and the controller is returned toward the "off" position, the lug 40 lifts one of the catches 85 and strikes against the end of the other catch and brings the controller to rest. The first catch then drops behind the lug and prevents it from rebounding.

It will be seen that when the bolt 29 enters the recess 31, the end of the plate 32 engages with a notch 41 in the hub 42 forming part of the cap-plate. By this means the controller is locked in its "off" position at the same time that the emergency devices are held in their inoperative positions, so that the motorman may take out the key and leave the controller without danger that it will be operated or the brakes applied. The engagement of the plate 32 with the hub also serves the purpose of making it necessary for the motorman to unlock the emergency devices before the controller can be turned into a running position, thereby preventing the motorman from locking the emergency devices so as to be inoperative during the time the controller is in a running position. Furthermore, the key cannot be withdrawn through the opening 37 until the controller is brought into the "off" position and the button depressed so as to bring the notch 41 into registration with the end of the plate and the opening 31 into registration with the bolt 29.

When it is desired to start the car, the motorman inserts the key and turns it, at the same time placing his hand upon the button so as to prevent the application of the brakes when the locking bolt is withdrawn. Thereafter, as long as the button is held depressed, the controller may be turned into any desired position; but, if at any time, either while the controller is in the "off" position or in a running position, the handle is released, the brake valve will be operated 115 and the brakes applied, in the manner previously described. Upon leaving the car the motorman removes the key while the button is still depressed, thereby locking both the brake devices and the controller. 130

What I claim as new and desire to secure by Letters Patent of the United States, is,—

1. In combination, a controller, an emergency device operated thereby, and a locking device adapted to engage with a fixed portion of the controller and with movable members of the controller and emergency device to lock the controller and emergency device in inoperative position.
2. In combination, a controller, an emergency device operated thereby, and a locking device adapted to engage with a fixed portion of the controller and with movable members of the controller and emergency device to lock the controller and emergency device in inoperative position, and a removable key for operating said locking device.
3. In a controller, a movable controller member, an emergency device, a governing member for said emergency device mounted upon said controller member, and a locking bolt adapted to engage recesses in a fixed portion of the controller, in said movable member and in said governing member.
4. In a controller, a movable controller member, an emergency device, a governing member for said emergency device mounted upon said controller member, a locking bolt adapted to engage recesses in a fixed portion 30 of the controller, in said movable member and in said governing member, and a detachable key for operating said locking bolt.
5. In a controller, a controller handle, an emergency device, an operating member for 35 said emergency device, a catch for restraining said operating member, and means associated with said controller handle for tripping said catch upon release of the controller handle.
6. In a controller, a controller handle, an emergency device, means for operating said device, a catch for restraining said operating means, and means associated with the controller handle for setting said operating 45 means and for tripping the catch upon release of the controller handle.
7. In a controller, a shaft, a handle on said shaft, an emergency device, a member for operating said emergency device, a catch for 50 restraining said member, a trip-device, slidably mounted upon the shaft and adapted in one position to trip said catch and in its other position to set said operating member, a spring for moving said trip-device in one 55 direction, and means associated with the controller handle for moving said trip-device in the other direction.
8. In a controller, a controller shaft, a handle on said shaft, an emergency device, a 60 rod for controlling said emergency device slidably mounted in an opening extending lengthwise of the shaft, and a locking bolt carried by said handle and adapted to engage with said rod.
9. In a controller, a controller shaft, a 65 handle on said shaft, an emergency device, a rod for controlling said emergency device slidably mounted in an opening extending lengthwise of the shaft, a locking bolt carried by said handle and adapted to engage with 70 said rod and with a fixed portion of the controller.
10. In a controller, a controller shaft, a handle on said shaft, an emergency device, a 75 rod for controlling said emergency device slidably mounted in an opening extending lengthwise of the shaft, a locking bolt carried by said handle and adapted to engage with said rod and with a fixed portion of the controller, and a detachable key for operating 80 said bolt.
11. In a controller, a shaft and an operating handle, an emergency controlling device, a spring-actuated arm for operating said device, a catch for restraining said arm, a 85 spring-actuated member slidably mounted in said shaft for tripping said catch, a button on said controller handle, and means operated by said button for moving said member to set the arm.
12. In a controller, a shaft and an operating handle, an emergency controlling device, a spring-actuated member for operating said device, a catch for locking said member, a 90 part on the controller shaft, a spring for moving said part to trip the catch, and means associated with the controller handle for moving said part to operate said member against the tension of its spring.
13. In a controller, a shaft and an operating handle, an emergency brake device, a spring-actuated member for operating said device, a catch for restraining said member, a part slidably mounted upon said shaft, a 95 spring for moving said part to trip the catch, and means associated with the controller handle for moving said part out of engagement with the catch and into engagement with a portion of said member to move said member into position for engaging said catch, 100 said means including a member adapted to be gripped by the operator.
14. In a controller, a shaft and an operating handle, an emergency brake device, a spring-actuated member for operating said 105 brake device, an arm projecting from said member adjacent the shaft, a catch for restraining said member, and an element slidably mounted upon said shaft and adapted to engage with said catch to trip the same 110 and with the arm to set the said member, a spring tending to move said element to its catch-tripping position, and a device on the controller handle movable relative to the handle for operating said element to engage 115 said arm.
15. In a controller, a shaft and an operating handle, a brake valve, a spring-actuated member for operating said valve, a catch for restraining said member, and means asso- 120 125 130

- ciated with the controller handle for setting said member in catch-engaging position and for tripping said catch when the handle is released.
5. 16. In combination, a controller having a revolute shaft, a spring tending normally to maintain said shaft in the "off" position, an emergency brake device arranged adjacent the shaft, an operating member for said 10 brake device, a catch for restraining said operating member, a cam on said shaft normally in the path of said catch for tripping the same, and means for depressing said cam out of the path of the catch.
15. 17. In combination, a controller having a revolute shaft, a spring tending normally to maintain said shaft in the "off" position, an emergency brake device arranged adjacent the shaft, an operating member for said 20 brake device, a catch for restraining said operating member, a cam on said shaft normally in the path of said catch for tripping the same, and means for depressing said cam out of the path of the catch and into engagement with said operating member to set the same.
25. 18. In combination, a controller having a revolute shaft and an operating handle, a spring tending normally to maintain said shaft in the "off" position, an emergency 30 brake device, an operating member for said brake device having an arm extending adjacent the shaft, a catch for restraining said operating member, a cam on the controller 35 shaft normally in the plane of the catch for tripping the same, and means associated
- with the controller handle for depressing said cam out of operative relation with the catch and into engagement with said arm for moving the operating member for the brake device into catch engaging position.
40. 19. In combination, a controller having a shaft and an operating handle, a spring tending to maintain said shaft in the "off" position, an emergency brake valve, an operating member for said brake valve, a catch for normally restraining said operating member, said catch and operating member having portions extending adjacent the shaft, a cam 45 slidably mounted upon said shaft, a spring tending to move said cam into the plane of the catch, and means associated with the controller handle for moving said cam out of the plane of the catch and into engagement with the valve-operating member for setting 50 the same.
5. 20. In combination, a controller having a revolute shaft and operating handle, a spring tending normally to maintain said shaft in the "off" position, an emergency 60 brake device, an operating member for said device, a catch for restraining said operating member, a part associated with said shaft for tripping the catch, and means associated with the controller handle for moving said 65 part into an inoperative position.

In witness whereof, I have hereunto set my hand this second day of March, 1906.

ARTHUR T. CROCKER.
